Primary Examiner — S. Bryan Reinholdt, Jr.*Assistant Examiner* — Andrew D Golson(74) *Attorney, Agent, or Firm* — Clement Cheng(57) **CLAIM**

The ornamental design for a chess board door as shown and described.

DESCRIPTION

FIG. 1 is a left perspective front view of the chess board door, the right perspective front view of which is a mirror image thereto.

FIG. 2 is a front view thereof.

FIG. 3 is a back view thereof.

FIG. 4 is a right side view thereof.

FIG. 5 is a left side view thereof.

FIG. 6 is an enlarged top view thereof; and,
FIG. 7 is an enlarged bottom view thereof.

The broken lines and the unshaded areas adjacent to them depict portions of the chess board door that form no part of the claim.
